H. O. REIDENBACH

SPRING STRUCTURE

Filed Feb. 10, 1923

FIG. I.

FIG. II.

FIG. III.

Inventor
Herman O. Reidenbach

Chappell & Carl

884

Attorneys:

UNITED STATES PATENT OFFICE.

HERMAN O. REIDENBACH, OF DETROIT, MICHIGAN, ASSIGNOR TO L. A. YOUNG INDUSTRIES, INC., OF DETROIT, MICHIGAN.

SPRING STRUCTURE.

Application filed February 10, 1923. Serial No. 618,248.

To all whom it may concern:

Be it known that I, HERMAN O. REIDENBACH, a citizen of the United States, residing at Detroit, county of Wayne, State of Michigan, have invented certain new and useful Improvements in Spring Structures, of which the following is a specification.

This invention relates to improvements in spring structures.

10 The main objects of this invention are:

First, to provide in a spring structure, such as cushion springs, bed springs and the like, an improved means for tying or connecting the ends of the springs.

15 Second, to provide an improved means for connecting the ends of springs in spring structures of the class described, which constitutes an effective support for the upholstery, mattress or the like, and one in which 20 there are no projecting parts to tear or wear the same.

Further objects, and objects pertaining to details and economies of the structure will 25 definitely appear from the detailed description to follow.

30 I accomplish the objects of my invention by the devices and means described in the following specification. The invention is clearly defined and pointed out in the claims.

A structure which is a preferred embodiment of my invention is clearly illustrated in the accompanying drawing forming a part of this application, in which:

35 Fig. I is a fragmentary plan view of a cushion structure embodying the features of my invention.

40 Fig. II is an enlarged fragmentary plan view showing structural details.

45 Fig. III is a detail view partially in vertical section on a line corresponding to line 3—3 of Figs. I and II, looking in the direction of the arrows.

Similar numerals of reference refer to 50 similar parts in all of the views.

In the accompanying drawing I have illustrated only such parts of a spring cushion structure as are deemed necessary to illustrate an adaptation or embodiment of my invention.

55 Referring to the drawing, the body springs 1 are preferably arranged in rows 2 as illustrated. The outer or border frame 2

is secured to the outer springs by the clips 55 as at 3. The structure illustrated is a miniature structure, that is, there are commonly more springs in a spring cushion structure than are here illustrated.

V-shaped tie members 4 are disposed in coacting pairs with their bights adjacent. 60 These bights have laterally offset loops 5 therein which are passed through the opening 6 in the clip plate 7. The tie wires 8 are arranged through these offsets or loops 65 so that the clip plates lie between the tie members and the tie wires, thus locking or securing the parts together.

The ends of the tie wires are secured to the border frame. The ends of the tie members are secured to adjacent springs. 70

With the parts thus formed and arranged they are very easily assembled, and when assembled the springs are effectively supported and a desirable grid-work is provided for supporting the upholstery or the 75 mattress.

I have illustrated and described my improvements in an embodiment which I have found very satisfactory. I have not attempted to illustrate various embodiments 80 and adaptations which I contemplate as I believe the disclosure made will enable those skilled in this art to embody my invention as may be desired.

Having thus described my invention, 85 what I claim as new and desire to secure by Letters Patent is:

1. In a spring structure, the combination of a border frame, a plurality of springs arranged in rows, V-shaped tie members disposed in coacting pairs with their ends connected to adjacent springs and their bights adjacent, said bights having lateral offsets 90 therein, clip plates having holes therein through which said offsets are disposed, and tie wires threaded through said offsets so that said clip plates lie between the tie members and tie wires, the ends of said tie wires being secured to said border frame.

2. In a spring structure, the combination 100 of a plurality of body springs, V-shaped tie members disposed in coacting pairs with their ends connected to adjacent springs and their bights adjacent, said bights having offset loops therein, clip members through 105 which said loops are disposed, and tie wires

threaded through said loops so that said clip plates lie between the tie wires and tie members.

3. In a spring structure, the combination 5 of a plurality of body springs, V-shaped tie members having their ends connected to adjacent springs and having lateral offsets

in their bights, clip members disposed on said lateral offsets, and tie wires threaded through said offsets so that the clip members 10 lie between the tie wires and tie members.

In witness whereof, I have hereunto set my hand and seal.

HERMAN O. REIDENBACH. [L. S.]
